MAGNETIC POWDER DISPENSER

Harry E. Kennedy, Berkeley, Calif., assignor to Union Carbide Corporation, a corporation of New York

Continuation of abandoned application Serial No. 488,820, February 17, 1955. This application January 16, 1957, Serial No. 634,584

8 Claims. (Cl. 302—51)

The present invention relates to novel apparatus for suspending in a stream of carrier gas a powdered welding composition having a magnetic component.

In my co-pending patent application Serial No. 481,906, now abandoned, entitled "Welding Process Employing Shielded Metal Arc," a process is disclosed wherein a powdered non-gas-evolving mineral material containing a magnetic component is suspended in a stream of shielding gas and conveyed therein to a point adjacent to the arcing end of a current-carrying consumable metal welding electrode, to which it adheres. The shielding gas, after conveying the powdered magnetic coating to the rod, is distributed about the arc zone in such a manner that it serves to shield the welding zone and the weld puddle from the air of the atmosphere. The powdered mineral material is a fused, bonded composite and contains a magnetic component which may comprise any suitable ferromagnetic material, such as iron powder or a powdered ferrite, whereby the powdered composite material is caused to adhere to the surface of a current-carrying or a permanently magnetic body.

It is the main object of the present invention to provide simple and rugged apparatus suitable for uniformly suspending powdered composite welding composition having a magnetic component in a stream of shielding gas at a controllable rate.

According to the present invention, the apparatus for suspending in a stream of carrier gas powdered material having a magnetic component comprises regulator means for controlling the discharge of said material from a supply thereof, magnetic conveyor means receiving said discharged material from said regulator means, and suspending gas conduit means receiving said conveyed material from said magnetic means. Preferably the regulator means comprises a tube receiving the material from a hopper, and the magnetic conveyor preferably comprises a magnetic surface movable under the tube, the tube being vertically adjustable to regulate the distance above the surface for the discharge orifice at the bottom of the tube, to deposit on the surface a layer of material of thus determined uniform thickness. The material is removed from the conveyor preferably by wiper means, and discharged into the suspending gas conduit means.

In the drawing:

Figure 1 is a vertical sectional view of a magnetic powder dispenser embodying the invention;

Figure 2 is a partial sectional view of the dispenser taken along the line 2—2 of Figure 1;

Figure 3 is a partial sectional view of the dispenser taken along the line 3—3 of Figure 2; and

Figure 4 is a partial elevated view of the dispenser taken along the line 4—4 of Figure 2 and showing in detail a part of the vibrator and magnetic drum drive mechanism.

In the preferred embodiment of the present invention shown in the drawings, apparatus for suspending powdered composite magnetic material in a stream of gas is provided having a closed material hopper discharging,

2

under the influence of gravity, into a communicating distributing chamber having positioned therein a rotating magnetic drum. The powdered magnetic material entering the distributing chamber adheres to and builds up as a layer on the surface of the rotating magnetic drum. As the drum rotates to a point approximately one half a turn beyond the point of material deposition, a scraper removes the material from the drum and the material passes, under the influence of gravity, to an outlet passage at the base of the distributing chamber. Thereupon, the material passes into an injector chamber where it is mixed with and suspended in a stream of carrier gas. The material is then carried in this stream of gas to the point of intended use.

More specifically, and referring to the figures of the drawing, a closed powdered material hopper 10, preferably of transparent material such as clear plastic, is provided having a conical base 12 converging to discharge port means 14. The top of hopper 10 is provided with a hopper fill plug 16 for supplying powdered material to the hopper.

Regulating tube means 18 is provided in hopper 10 and extends from the hopper to a point at which manual adjustment can be made. The regulating tube 18 comprises an elongated hollow cylindrical tube provided at the upper end thereof with threads 20 and a knob 22 for rotating the tube. Threads 20 are engaged in the top 24 of hopper 10, and the position of regulating tube 18 can be raised or lowered by turning knob 22. The lower end of regulating tube 18 passes through discharge port means 14 and contains passages 26 communicating between the lower portion of hopper 10 and the interior 28 of regulating tube 18, through which powdered material is passed from the interior of hopper 10 to the interior 28 of regulating tube 18.

A material distributing chamber block 30 having a closed distributing chamber 32 is positioned below hopper 10 so that chamber 32 is in communication with the discharge end of interior 28 of regulating tube 18. A rotating magnetic drum 34 is positioned in chamber 32, below the discharge end of regulating tube 18, so as to receive the powdered material discharging therefrom. The powdered material builds up to form a coating 36 on the surface 38 of magnetic drum 34 and the thickness of the coating is determined by the clearance 40 between the discharge end of regulating tube 18 and the surface 38 of rotating drum 34. Clearance 40 is adjustable by turning knob 22 of regulating tube 18 to vary the longitudinal positioning of the regulating tube. Material wiping means 42 is positioned in chamber 32 below rotating magnetic drum 34 so as to remove the coating of powdered material from the drum and allow it to pass, under the influence of gravity, through outlet passage means 44 of the distributing chamber 32.

The powdered material passes through conduit means 46 into injector chamber 48, into which a stream of carrier gas is injected at high velocity from injector 50 (communicating with inlet gas conduit means 52). The powdered material suspended in the gas stream in chamber 48 is discharged through outlet conduit means 54 to the point of intended use.

The interior of closed hopper 10 and closed distributing chamber 32 is at a positive pressure of gas established by the back pressure in the system from the gas conduit. A pressure equalizing line may be run from the carrier gas conduit 52 to the hopper 10, if desired.

Vibrating means is provided for preventing clogging of the powdered material in the hopper and insuring a uniform rate of flow of material from the hopper through regulating tube 18. As shown in Figures 2—4 of the drawing, driving means is provided comprising a driving chain 56 and a driven sprocket 58 which, in turn, drives both

the vibrating means and the rotating magnetic drum 34 through shaft 60.

The vibrating mechanism comprises hammer cam 62 which actuates hammer 64 against spring 66 so as to deliver impact to anvil 68 rigidly mounted on the distributing chamber block 30. This vibration delivered to the distributing chamber block 30 is transmitted to hopper 10 which is securely mounted thereon.

Shaft 60 is also mounted to drive rotating magnetic drum 34 within chamber 32. The rotating magnetic drum comprises a permanent magnet 70 enclosed in an outer casing 72 of ferromagnetic material, such as steel, whereby the magnetic circuit is completed to the powdered magnetic material deposited on the surface 38 of magnetic drum 34.

An electric holding coil 76 is provided around discharge port means 14 of hopper 10 so as to surround the passages 26 of regulating tube 18. Coil 76 is energized when no powdered magnetic material is needed, thereby stopping the passage of material through tube 18 to chamber 32 and preventing the flooding of chamber 32 with powdered material.

It has been found that the powder dispenser of the invention is capable of very closely regulating the rate of feed of powdered magnetic material from the hopper to the carrier gas stream and thereby uniformly distributing powdered magnetic material in the carrier gas stream. Means are provided for easily insuring against failure in the supply of powdered magnetic material which, if it occurred, would necessitate a stoppage in the welding operation in which the gas-borne powdered magnetic material is utilized.

A dispenser of the type shown in the drawing was employed to suspend powdered welding composition in a stream of carbon dioxide carrier gas at powder flow rates of between about 10 and 150 grams per minute. This dispenser employed a regulating tube having three passages $1\frac{1}{2}$ inches x $1\frac{1}{8}$ inches an internal diameter of $\frac{5}{8}$ inch, and clearance of $\frac{1}{16}$ inch between the discharge end of the regulating tube and the surface of the magnetic drum. It was found that this dispenser was operable over a carrier gas feed rate of from about 5 to 50 c.f.h., with about 5 c.f.h. the minimum operable gas flow rate for satisfactorily suspending finely powdered material (100xD), and about 10-15 c.f.h. the minimum operable gas flow rate for satisfactorily suspending coarser particles (20xD).

This application is a continuation of my copending application Serial No. 488,820 filed February 17, 1955, now abandoned.

What is claimed is:

1. In apparatus for suspending in a stream of carrier gas a powdered composite material having a magnetic component including a material hopper communicating at the base with discharge port means, a material distributing chamber in communication with said discharge port means and having an outlet passage, and suspending gas conduit means in communication with said outlet passage, the improvement which comprises magnetic conveyor means in said distributing chamber, horizontal orifice means positioned above said magnetic conveyor means for discharging a quantity of said composite material onto the surface of said magnetic conveyor to form thereon a rectangular layer of said composite material of uniform thickness, and means for regulating the vertical clearance between said horizontal orifice means and said magnetic conveyor means to adjust the thickness of said rectangular layer, and means for removing said layer of composite material from said magnetic conveyor and discharging it to said outlet passage.

2. Apparatus in accordance with claim 1, in which said hopper is securely mounted on said distributing chamber, in combination with means actuated by the same source of power for driving said magnetic conveyor means and for vibrating said distributing chamber, and

such vibrations are transmitted to said hopper for preventing the clogging of said material therein.

3. A distributing chamber having an inlet passage for discharging from a supply and a vertically aligned outlet 5 delivering to a carrier gas stream suspension conduit a powdered composite material having a magnetic component, comprising magnetic conveyor means mounted in said chamber, a hollow regulator tube extending from above into said chamber to a variable height above said magnetic conveyor means for discharging from said inlet a controlled quantity of said material onto said magnetic conveyor means to form thereon a continuous layer of said material, and wiper means for removing said layer from said magnetic conveyor means and passing it 15 through said vertically aligned outlet passage to said carrier gas stream suspension conduit.

4. A distributing chamber for discharging from a supply and delivering to a carrier gas stream suspension conduit a powdered composite material having a magnetic component, comprising magnetic conveyor means 20 mounted in said chamber, a hollow regulator tube extending from above into said chamber to a variable height above said magnetic conveyor means for discharging a controlled quantity of said material onto said magnetic conveyor means to form thereon a continuous layer of said material, wiper means for removing said layer from said magnetic conveyor means and passing it to said carrier gas stream suspension conduit, and means for vibrating said chamber to prevent clogging of said composite material.

5. In apparatus for suspending in a stream of carrier gas a powdered composite material having a ferromagnetic component including a closed material hopper communicating at the base with discharge port means, a closed 35 material distributing chamber in communication with said discharge port means and having at its base an outlet passage, and suspending gas conduit means in communication with said outlet passage for suspending said composite material in a stream of carrier gas conducted 40 therethrough; the improvement which comprises magnetic drum means rotatably mounted in said distributing chamber, regulator tube means positioned above said magnetic drum means for discharging a controlled quantity of said composite material on the surface of said 45 rotating magnetic drum means to collect thereon a layer of said composite material; and drum wiper means positioned at and contacting the lower portion of said magnetic drum means for wiping said collected layer of composite material from said rotating magnetic drum means, and permitting it to pass under gravity to said outlet 50 passage.

6. In apparatus for suspending in a stream of carrier gas a powdered composite material having a ferromagnetic component including a closed material hopper communicating at its base with discharge port means, a closed material distributing chamber in communication with said discharge port means and having at its base an outlet 55 passage, and suspending gas conduit means in communication with said outlet passage for suspending said composite material in a stream of carrier gas conducted therethrough; the improvement which comprises magnetic drum means rotatably mounted in said distributing chamber, regulator tube means positioned in said hopper and extending through said discharge port means for discharging a controlled quantity of said composite material on the surface of said rotating magnetic drum to collect thereon a layer of said composite material, an injector chamber including a gas injector in said suspending gas conduit means for suspending said composite material in a carrier gas stream, and drum wiper means 60 positioned at and contacting the lower portion of said magnetic drum means for wiping said collected layer of composite material from said rotating magnetic drum and permitting it to pass under gravity to said outlet passage.

7. A distributing chamber for discharging from a hopper supply and delivering to a carrier gas stream suspension conduit a powdered composite material having a ferromagnetic component comprising a magnetic drum rotatably mounted in said chamber, a hollow regulator tube extending from above into said chamber to a variable height above said rotating drum for discharging a controlled quantity of said composite material on the surface of said drum to collect thereon a continuous layer of said composite material, and drum wiper means positioned at and contacting the lower portion of said magnetic drum for wiping said collected layer of composite material from said drum and allowing it to pass under gravity to the carrier gas stream suspension conduit.

8. In apparatus for suspending in a stream of carrier gas a powdered material having a magnetic component, means for supplying said material, regulator means for controlling the discharge of said material from said sup-

ply means, magnetic conveyor means receiving said discharged material from said regulator means to form a layer thereof on said magnetic conveyor means, means for passing said layer of material from said magnetic conveyor into said stream of carrier gas, and electric holding coil means for arresting the flow of said material from said supply means to said regulator means.
